UNITED STATES PATENT OFFICE.

MILO D. RATHBUN, OF GRAND RAPIDS, MICHIGAN, ASSIGNOR TO THOMAS E. WEIR, OF MUNCIE, INDIANA.

SHIELD FOR MOTOR-CAR RADIATORS.

Application filed January 3, 1922, Serial No. 526,822. Renewed May 23, 1925.

To all whom it may concern:

Be it known that I, Milo D. RATHBUN, citizen of the United States, residing at Grand Rapids, in the county of Kent and State of Michigan, have invented certain new and useful Improvements in Shields for Motor-Car Radiators, of which the following is a specification.

This invention relates to improvements in shields for radiators of motor cars, and has reference especially to shields of that class in which the openings in the shield are provided with movable closure devices whereby the area of the openings may be varied.

15 The general object of the present invention is to provide a shield device, to be connected to the radiator and which device is operable by the driver, from his seated position in the car, to control the air current flowing through the radiator. More specific objects of the invention are to provide a device of the kind described which will be durable, light in weight, dependable, economical of manufacture, and easy to install 25 and to operate.

The invention consists of a shield or frame made of imperforate material adapted to be attached to the front of the radiator, and in which frame are openings, closed by movable doors, the said doors, after the manner of shutters, having devices between them so arranged that when actuated the doors are moved to open or close the said openings; and means operable by the driver to actuate 30 the said devices.

A preferred form of embodiment of my invention and for carrying the invention into effect, consists of the new construction, combination and arrangement of parts shown in 40 the accompanying drawings and described in the following specification. The invention is defined in the appended claims.

In the drawings, the several parts of the invention are identified by suitable characters of reference applied thereto in the different views, in which—

Figure 1 is a front view of my improved radiator shield.

Figure 2 is a top plan view; and

50 Figure 3 is a rear view.

Figure 4 is a vertical sectional view taken on the line 4—4 in Figure 1.

Figure 5 is a horizontal sectional view of a portion of the top plate taken on the line

5 of Fig. 1 and as seen in the direction indicated by the arrow.

Figure 6 is an enlarged horizontal sectional view taken on the line 6—6 in Figure 1 and in the direction indicated by the arrow.

Figure 7 is a detached enlarged view of the lower portion of one of the shutter-like doors.

Figure 8 is a vertical sectional view taken on the line 8—8 in Figure 7.

In this showing of my invention, the shield, made of sheet metal, is of dimensions suitable to be placed at and secured to the front of any standard flat faced form of automobile radiator. Features of my invention are the details of construction and combination whereby the shield proper, the doors, and all the connections, are not only capable of economical construction, but the device as an entirety is rugged, durable and easy to install.

The top and bottom plates A and B, respectively, and the side plates C and D may be made of wood or of cast metal, but are preferably of sheet steel of twenty to twenty two gauge thickness. By reference to Figure 3 the construction of these plates may readily be understood. The curled outer edge of each of these plates lends stiffness to the plate, constitutes a finish for the outer portion of the plate, and is adapted to be brought down to gripping engagement with asbestos filler (not shown) and which may be used in combination with the plate.

To lend additional stiffness to the side or vertical plates C and D, each is provided with a bead or crimp near its outer edge. These plates secured together at their ends, may be so secured, by brazing and by rivets E³. The interior edge of the plate A and of the plate B is bent at a right angle to form cheeks A¹ and B¹, and the jambs A² and B² respectively. Similarly, the inner edges of the plates C and D are formed to provide the cheeks C¹ and D¹ and the jambs C² and D².

Plate E is secured at its ends to the plates A and B, its edges being bent to form the cheeks E¹ and the jambs E²; the said plate being at central position, two vertical openings in the shield frame are provided. In each of these openings is arranged a door G made of sheet steel its edges being bent inwardly to retain the asbestos sheet G¹. The

hinge rod H has its ends journaled in holes provided therefor in the cheeks A¹ and B¹. The said doors are of dimension to occupy the said openings with proper clearance, and when closed to rest immediately against the jambs. A bracket K having an eyelet therein is secured to the bottom portion of each door. A connecting rod L with its ends disposed loosely in the said brackets, has a ball shaped head L¹ on each end.

An actuating bar M having a head M¹ with a transverse bore through which the rod L may slide freely, is passed through an aperture in the plate B, and has bearing in block M² secured to plate B. A coil spring O between the block M² and the collar M³, urges the bar M normally to the retracted position shown. The rear end of the actuating bar is threaded and adapted to receive 20 reach-rod connections (not shown) to extend to proper location in the car so that the car driver may move the actuating bar.

The normal position of the doors is closed, as shown in Figure 6. In this position the doors lie against the cheeks and jambs and passing of air through the shield is prevented, this being very essential in the conservation of the radiator and of the motor during the cold weather. To open the doors, 30 the driver pushes the actuating bar forward. With the consequent movement forwardly of the connecting rod L and the doors are swung to an open position, as shown by the dotted lines in Figure 6.

35. What I claim as my invention, and desire to secure by Letters Patent, is—

1. A shield for an automobile radiator, comprising a frame adapted to be fastened

to the radiator and being provided with parallel openings, a door hinged at each of said openings, a bracket having an eyelet secured on the end of each door, a connecting rod having its ends disposed loosely in the said eyelets, and an actuating bar operable through the said frame, to move the said connecting rod.

2. In a shield for automobile radiators, a frame comprising top and bottom plates having interior opposed inturned flanges, side plates having interior opposed inturned flanges, a central plate having an inturned flange on both sides, doors to fit the openings formed by the said plates, hinge bars through said doors and journaled in said flanges, a bracket having an eyelet secured on the end of each door, a connecting rod having its ends disposed loosely in said eyelets, an actuating bar journaled slidably at a point between the doors and having a head with a transverse bore to engage said connecting bar loosely, and a spring to urge the said actuating bar to retracted position.

3. A shield of the kind described, comprising a frame adapted to be fastened to a radiator and being provided with vertical openings, a door hinged at each of said openings, a bracket having an eyelet secured on the end of each door, a connecting rod having its end portions disposed loosely in said eyelets, a knob on each end of the said connecting rod, and an actuating element operable through the frame, to move the said connecting rod.

In testimony whereof I affix my signature.

MILO D. RATHBUN.
